CLAIM

I claim the ornamental design for a vacuum lid, as shown and described.

DESCRIPTION

FIG. 1 is a front perspective view of a first embodiment of my vacuum lid;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a rear perspective view thereof;
FIG. 9 is a front perspective view of a second embodiment thereof;
FIG. 10 is a front view of FIG. 9;
FIG. 11 is a rear view of FIG. 9;
FIG. 12 is a left side view of FIG. 9;
FIG. 13 is a right side view of FIG. 9;
FIG. 14 is a top view of FIG. 9;
FIG. 15 is a bottom view of FIG. 9;
FIG. 16 is a rear perspective view of FIG. 9;
FIG. 17 is a front perspective view of the first embodiment showing additional environmental structure; and,
FIG. 18 is a front perspective view of the second embodiment showing additional environmental structure.
The dashed lines form no part of the claimed design.
